ELECTRON DISCHARGE DEVICE

Filed Aug. 13, 1919

Inventor:
Robert W. King

by *J. E. Roberts* Atty.

UNITED STATES PATENT OFFICE.

ROBERT W. KING, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed August 13, 1919. Serial No. 317,314.

To all whom it may concern:

- Be it known that I, ROBERT W. KING, a citizen of the United States, residing at New York, in the county of New York and State of New York, have invented certain new and useful Improvements in Electron-Discharge Devices, of which the following is a full, clear, concise, and exact description.
- 10 The invention relates to improvements in the mounting of electrodes for vacuum tube devices, and by way of example is illustrated and described as embodied in an electron discharge device of the audion type.
- 15 It has been common in vacuum tube devices to support one or more of the electrodes from a glass rod or arbor which projects into the tube. The use of a fragile support, such as a glass rod, is objectionable, however, due to the frail character of the support.
- An object of the present invention is to avoid, to a large extent at least, the use of a glass supporting structure for an electrode 25 or electrodes to the end that a stronger and more rugged mounting may be employed instead. This is accomplished, according to the present invention, by providing a metallic supporting connection between the 30 plate electrodes and the press or squash in which the leading-in wires are sealed. The support for the grid and filament is provided in the form of a block of insulating material connected to one of the plate electrodes.
- 35 For further details of the invention, reference may be made to the drawing in which the figure illustrates in perspective a vacuum tube embodying the features of this invention. Referring in detail to the drawings, the vacuum tube 1 is provided with the usual inwardly projecting neck 2, which terminates in a press 3 in which the leading-in wires are sealed. The electrodes in 40 this case comprise an M-shaped filament 4, a double grid surface 5, and a double plate electrode 6. Filament 4 is supported at its lower ends by wires 7, 8 and 9, the wires 7 and 9 being extended to provide terminals 50 for supplying current to the filament. The plate electrode 6 comprises two plate-shaped elements 10 and 11, which have upturned edges as shown. At the top of or above the plate element 10 is fastened a strip of insulating material 12 which may be of
- lavite. The block 12 is fastened to the plate 10 by the rods 13 and 14 which are welded to the plate 10 at the lower ends and suitably anchored in apertures in block 12 at their upper ends. The wire 15 fastened in the block 12 and having the coils 16 intermediate its length serves to resiliently support the filament 4, contacting with the bights thereof at 17 and 18, as shown.
- The grid is supported at its lower end by the wire 19 welded to the grid and extending through the press to form a leading-in wire. The upper end of the grid is supported from the block 12 by the wire 20 connected thereto and to the grid, and by a similar wire 21 at the other side of the electrode structure.
- The plate elements 10 and 11 are electrically and mechanically connected together by the wires 22, 23 welded to the upturned edges of the plate elements, and by similar wires at the other side of the plate electrode. The plate electrode structure is a unitary one and is separated from the press 3 by metallic means such as the U-shaped metal pieces 24, 25, the arms of which are welded to the plate elements 10 and 11. The U-shaped supports 24 and 25 are suitably fastened to the press, for instance, by integral extensions 26 and 27 respectively, which extend into and are sealed into the press 3.
- This vacuum tube is not limited for use in any particular vacuum tube circuit, but as illustrating one type of circuit that may be employed reference is made to the patent to Arnold 1,129,942, March 2, 1915.
- While the electrode supporting features have been shown as applied to electron discharge devices of the audion type, they may be applied to X-ray or other vacuum tubes.
- What is claimed is:
1. A vacuum tube comprising a press, anode, cathode and control electrodes, a forked metallic member mounted on said press and supportingly associated with said anode, and supporting connections between said anode and control electrode.
  2. A vacuum tube comprising a press, parallel plates, a plurality of forked metallic members mounted on said press, each arm of each of said members being supportingly associated with each of said plates.
  3. A vacuum tube comprising a press, metallic members having arms mounted on said press, the corresponding arms of each mem.

ber extending parallel to each other and plates supported by said arms in parallel relation to each other.

4. A vacuum tube comprising a press, a cathode, an anode and a grid, said anode comprising parallel plate surfaces, a plurality of parallel metallic members mounted on said press, and a plurality of arms projecting from each of said metallic members, each of said arms being connected to one of said plate surfaces.

5. A vacuum tube comprising a plurality of electrodes one of which is a plate electrode, insulating material supported by said plate electrode above one edge thereof, and a supporting connection from said insulating material to one of said other electrodes.

6. A vacuum tube comprising a cathode, a grid and an anode, insulating material supported by said anode above one edge thereof, 20 and supporting connections from said insulating material to said grid and cathode.

7. An electron discharge device comprising a vessel having a stem, an anode supported from said stem, members carried by 25 said anode and projecting beyond one edge thereof, a body of insulating material supported by said members, a cathode and a supporting connection from said insulating body to said cathode.

In witness whereof, I hereunto subscribe my name this 11th day of August, A. D. 1919.

ROBERT W. KING.

DISCLAIMER

1,479,991.—*Robert W. King, New York, N. Y. ELECTRON DISCHARGE DEVICE.*
Patent dated January 8, 1924. Disclaimer filed August 8, 1931, by the assignee,
Western Electric Company, Incorporated.

Hereby enters this disclaimer relative to claims 5 and 6 of said Letters Patent to wit:
To the combination of elements set forth in claims 5 and 6 of said Letters Patent,
except as the same are embodied in a vacuum tube wherein the insulating material is
separated by an intervening space from the edge of the plate electrode or anode by
which it is supported.
